MULTIPLE CONNECTOR BLOCK

William Ludlow Schumacher, Camp Hill, Pa., assignor to
AMP Incorporated, Harrisburg, Pa.

Filed Jan. 15, 1964, Ser. No. 78,198

Term of patent 14 years

(Cl. D26—1)

FIGURE 1 is an exploded perspective view of a multi-connector block showing my new design;

FIGURE 2 is a similar view taken from the opposite end;

FIGURE 3 is an elevational view with the parts in assembled condition;

FIGURE 4 is an elevational view taken from the left of FIGURE 3; and

FIGURE 5 is an elevational view taken from the right of FIGURE 3.

I claim:

The ornamental design for multiple connector block, as shown.
